UNITED STATES PATENT OFFICE.

ARTHUR A. BYERLEIN, OF TOLEDO, OHIO, ASSIGNOR TO THE TOLEDO MACHINE AND TOOL COMPANY, OF TOLEDO, OHIO, A CORPORATION OF OHIO.

DRAWING PRESS.

Application filed October 6, 1923. Serial No. 666,883.

This invention relates to drawing or toggle presses and has for its object the provision of a simple and efficient mechanism of novel and unique construction and arrangement of parts for communicating the requisite movements and dwell to the blank holder from the customary crank shaft of the press.

The invention is fully described in the following specification, and while in its broader aspect, it is capable of embodiment in numerous forms, a preferred embodiment thereof is illustrated in the accompanying drawings, in which—

Fig. 1 is a front elevation of a drawing press embodying the invention, with parts thereof broken away and with the blank holder in lowered position. Fig. 2 is a substantially central vertical section thereof, on the line 2—2 in Fig. 1. Fig. 3 is a fragmentary top view thereof, Figs. 4 and 5 are sections similar to Fig. 2 showing different positions of the parts, and Figs. 6 and 7 are diagrammatic views of still other positions of the parts.

Referring to the drawings, 1 designates the frame of the drawing press provided with the customary top arch 2 formed, in the present instance, of spaced transverse members, 3 the blank holder mounted for vertical reciprocatory movements in guides formed by the frame sides, and 4 the plunger, which operates, in the present instance, through the blank holder 3 and carries the forming die. The main operating crank shaft 5 of the press is mounted in the customary manner above the plunger and has one or more of its cranks operatively connected to the plunger by connecting rods 6.

In carrying out my invention I provide the top arch 2 with a hollow frame part 7 open at its top and bottom and of rectangular form in cross section. A rock-shaft 8 is mounted in the frame part 7 above the arch 2 and in parallel relation to the crank-shaft 5 and carries a lever member 9 for vertical rocking movements, said member having the arms 9^a and 9^b projecting in opposite directions from the shaft. A connecting rod 10 is mounted at its lower end on a centrally disposed crank of the crank-shaft 5 and extends upward through the space between the members of the frame top arch 2 into the top frame 7 and connects at its upper end to the arm 9^a of the lever 9

whereby rocking movements are communicated to the lever from a turning of the crank-shaft 5.

The frame part 7, in the present instance, forms guides 10 and 11 at opposite sides of the shaft 8 in which slides 12 and 13 are respectively mounted for vertical reciprocatory movements. Shafts 14 and 15 are carried by the frame part 7 and project through slots 16 and 17 in the respective slides 12 and 13, whereby the slides are permitted to have limited reciprocatory movements relative thereto. A shaft 18 is carried by the slide 12 above the shaft 14 and these shafts are connected together by a set of toggle links 19, so that breaking and straightening out movements of the toggle links impart reciprocatory movements to the slide 12. A set of toggle links 20 in like manner connects the shaft 15 with a shaft 21 on the slide 14, except that the shaft 12 is disposed below the shaft 15.

The lever arm 9^a is connected by a link 22 to one of the links of the set 19, and a link 23 connects the arm 9^b of the lever 9 to one of the links 20 so that rocking movements of the lever 9 impart simultaneous breaking and straightening out movements to the sets of toggle links 19 and 20 and corresponding reciprocatory movements to the slides 12 and 13, except that they are moved in opposite directions, one moving upward while the other moves downward, and vice versa.

Rock shafts 24 and 25 are mounted in the frame 1 at opposite sides of the crank-shaft 5, the shaft 24 being disposed adjacent to and without the lower end of the slide 12, and the shaft 25 being disposed adjacent to and within the lower end of the slide 13. The shaft 24 has a centrally disposed arm 26 projecting inwardly therefrom and connected by a link 27 to the lower end of the slide 12 and the shaft 25 has an outwardly projecting centrally disposed arm 28 connected by a link 29 to the lower end of the slide 13, the connections between the slides 12 and 13 and the respective shafts 24 and 25 being such that corresponding rocking movements are communicated to the shafts from opposed reciprocatory movements of the slides, as is apparent.

The shaft 24 is provided near each end with an arm 30 connected by a respective

link 31 to a boss 32 projecting outward from the adjacent side of the blank-holder 3, and the shaft 25 has an arm 33 projecting therefrom near each end and connected by a link 34 to a respective boss 35 on the adjacent side of the blank-holder 3. The connections between the slides 12 and 13 and the blank-holder are such, in the present instance, that when the slide 12 is at the upper extremity 10 of its movement and the slide 13 is at the lower extremity of its movement, the blank-holder 3 will be at the lower point of its movement, and vice versa. This is accomplished by extending the arm 26 upward and inwardly at substantially a 45 degree angle to a vertical when the arms 30 are in downwardly extended vertical position and by extending the arm 28 outward and downward a substantially 45 degree angle to a vertical 15 when the arms 33 are in downwardly extended vertical position.

It is evident that the means which I have employed for communicating the requisite reciprocating movements and dwell to the blank holder 3 is comparatively simple in its construction and in its present embodiment comprises a single operating connection with the crank shaft.

I wish it understood that my invention is not limited to any specific construction, arrangement or form of the parts, as it is capable of embodiment in numerous forms without departing from the spirit of the claims.

Having thus described my invention, what I claim as new and desire to secure by Letters Patent, is,—

1. In combination with the frame, crank shaft and reciprocating blank holder of a drawing press, a lever fulcrumed midway of the frame and above the crank shaft, and having arms projecting towards opposite sides of the frame, operative connections between each arm and the blank holder on the side of the frame towards which the respective arm projects, and driving connections from the crank shaft to the lever.

2. In combination with the frame, crank shaft and reciprocating blank holder of a drawing press, a lever fulcrumed midway of the frame and above the crank shaft, and having arms projecting towards opposite sides of the frame, operative connections between each arm and the blank holder on the side of the frame towards which the respective arm projects, and a link connecting an arm of the lever to a crank on the shaft.

3. The combination with the frame, crank shaft and reciprocally movable blank holder of a drawing press, of an oscillatory rocker member having oppositely projecting arms, operating connection between the rocker member and crank shaft, and a separate connection between each arm of the rocker member and the respective side of the blank

holder for communicating reciprocating movements to the blank holder from rocking movements to the rocker member.

4. The combination with the frame, crank shaft and reciprocally movable blank holder of a drawing press, of a two-armed lever carried for vertical rocking movements by the frame in vertically spaced relation to the crank shaft, operating connection between the crank-shaft and lever, and a separate connection between each arm of the lever and the respective side of the blank holder for communicating predetermined reciprocating movements to the latter from rocking movements of the former, each of said connections including a set of toggle links anchored at one end to the frame.

5. The combination with the frame, crank shaft and reciprocating movable blank holder of a drawing press, of a vertically rockable lever carried by the frame in vertically spaced relation to the crank shaft, an operating connection between the crank shaft and lever, a reciprocally movable member at each side of the frame, a connection between each member and the adjacent arm of the lever for imparting reciprocating movements to the member from rocking movements of the lever, said members having simultaneous movements in opposite directions when the lever is rocked, and connection between each member and the respective side of the blank holder for communicating reciprocating movements to the blank holder when the members are reciprocated.

6. The combination with the frame, crank shaft and the reciprocally movable blank-holder of a drawing press, of a vertically rockable two-armed lever mounted in the frame in vertically spaced relation to the crank shaft, an operating connection between the crank shaft and lever, a rock-shaft mounted in the frame at each side thereof, connection between each rock-shaft and the blank-holder for reciprocating the latter from rocking movements of the former, and connection between each arm of the lever and a respective rock shaft for communicating like rocking movements to both rock shafts from a rocking movement of the lever.

7. In combination with the frame, crank shaft and reciprocally movable blank holder of a drawing press, vertically movable slides above opposite sides of the blank holder, connections between each slide and the side of the blank holder directly therebeneath, a toggle for each slide having one end pivoted to the frame and the other end pivoted to the slide in vertically spaced relation to the first said pivot, the parts being so proportioned that the toggle is substantially straight when the holder is in holding position, a lever fulcrumed midway between the

slides and having arms projecting towards the toggles, a link connecting each toggle to the adjacent arm of the lever, the parts being so proportioned that the links and arms are substantially in line when the holder is in holding position, and operative connections between the lever and crank shaft.

8. The combination with the frame, crank shaft and reciprocally movable blank holders of a drawing press, of a rocker member mounted in the frame for vertical rocking movements, connection between the rocker member and crank shaft for operating one from the other, a vertically movable slide mounted in the frame at each side of the rocker member, connections between the rocker member and slides for imparting opposed reciprocating movements to the slides from rocking movements of the member, and connection between the slides and blank holders for operating the latter for movements of the slides.

9. The combination with the frame, crank shaft and reciprocally movable blank holders of a drawing press, of a rocker member mounted in the frame for vertical rocking movements, connection between the rocker member and crank shaft for operating one from the other, a vertically movable slide mounted in the frame at each side of the rocker member, connections between the rocker member and slides for imparting opposed reciprocating movements to the slides from rocking movements of the member, a rock shaft mounted in the frame for each slide, connections between the slides and respective rock shafts for imparting like rocking movements to the shafts from opposed movements of the slides, and connection between the rock shafts and blank holder for operating the latter from rocking movements of the shaft.

10. The combination with the frame, crank shaft and reciprocally movable blank holder of a drawing press, of a rocker lever mounted in the frame above the crank shaft, operating connection between the crank shaft and lever, a slide mounted in the frame adjacent to each end of the lever, means, including a set of toggle links, connecting each end of the lever to a respective slide and to the frame whereby opposed reciprocating movements are imparted to the slides from rocking movements of the lever, a rock shaft mounted in the frame adjacent to the lower end of each slide, connection between each slide and the respective rock shaft for imparting like rocking movements to the rock shaft from opposed reciprocating movements of the slides, and connection between each rock shaft and the blank holder for imparting operating movements to the latter from rocking movements of the former.

11. The combination with the frame, crank

shaft, and reciprocating blank holder of a drawing press, of a rock shaft mounted in the frame above and parallel with the crank shaft, connections between the rock shaft and crank shaft to oscillate the former from the latter, reciprocable slides on opposite sides of the axis of the rock shaft, means including a toggle for connecting each slide to the rock shaft, and means including a toggle for connecting each slide with the blank holder.

12. The combination with the frame, crank shaft, and reciprocating blank holder of a drawing press, of a rock shaft mounted in the frame above and parallel with the crank shaft, connections between the rock shaft and crank shaft to oscillate the former from the latter, reciprocable slides on opposite sides of the axis of the crank shaft, means including a toggle for connecting each slide to the rock shaft, and a toggle for connecting each slide to the blank holder, the relation of the parts being such that the said toggles are all straightened at the time blank holder is in holding position.

13. In combination with the frame, crank shaft and reciprocally movable blank holder of a drawing press, operative means for the opposite sides of the blank holder, each comprising a rock shaft journaled in the frame above the respective side, arms on the rock shaft, a link connecting one of the arms to the holder and proportioned so that they are substantially in line when the holder is in holding position, a slide above the rock shaft, a link connecting the slide to an arm on the shaft, a pivot on the slide, a vertically spaced pivot on the frame and a toggle having its ends mounted on the pivots and proportioned to be substantially straight when the holder is in holding position, a lever fulcrumed midway between the slides and having an arm extending towards each, a link connecting each arm of the lever with the knuckle of the toggle towards which it extends, the arm and link being so proportioned that they are substantially in line when the toggle is straightened, and means connecting the lever to the crank shaft.

14. In combination with the frame, crank shaft and reciprocally movable blank holder of a drawing press, operative means for the opposite sides of the blank holder, each comprising a rock shaft journaled in the frame above the respective side, arms on the rock shaft, a link connecting one of the arms to the holder and proportioned so that they are substantially in line when the holder is in holding position, a slide above the rock shaft, a link connecting the slide to one arm on the shaft, a pivot on the slide, a vertically spaced pivot on the frame and a toggle having its ends mounted on the pivots and proportioned to be substantially straight when the holder is in holding position, a lever fulcrumed midway between the slides

and having an arm extending towards each, a link connecting each arm of the lever with the knuckle of the toggle towards which it extends, the arm and link being so proportioned that they are substantially in line when the toggle is straightened, and a link connecting an arm of the lever to a crank on the crank shaft.

15. A press comprising a crank shaft, a blank-holder, and means for operating said blank-holder, said means comprising rocking parts at each side of the press turning on axes parallel to said crank shaft, toggles between said rocking parts and said blank-holder, a second rocking part nearer the middle of the press disposed above and turning on an axis parallel to said first rocking parts and crank shaft, connections between intermediate portions of said first and second rocking parts for transmitting movement from the latter to the former, and an operative connection between said crank shaft and second rocking part.

16. A press comprising a crank shaft, a blank-holder, and means for operating said blank-holder, said means comprising rocking parts at each side of the press turning on axes parallel to the crank shaft, toggles between said rocking parts and blank-holder, a second rocking part nearer the middle of the press, disposed above and turning on an axis parallel to said first rocking parts and crank shaft, connections between intermediate portions of said first and second rocking parts for transmitting movement from

the latter to the former, and an operative driving connection between the middle of the crank shaft and said second rocking part.

17. In a toggle press, a blank-holder, a single rock shaft disposed centrally above the blank-holder, a pair of rock shafts disposed below and at opposite sides of the single rock shaft, means for rocking the single rock shaft, means connecting the single rock shaft to each of said other rock shafts to impart predetermined rocking movements to the latter from the former, said means including reciprocatory movable members operating in vertical planes, and means connecting said lower rock shafts to the blank holder for imparting reciprocatory movements to the latter from rocking movements of the former.

18. In a toggle press, a frame, a rock shaft in said frame, means for rocking said rock shaft, a pair of rock shafts disposed below and at each side of said first rock shaft, a slide intermediate each of said last rock shafts and said first rock shaft, means for connecting each slide to said first rock shaft, means for connecting each slide to one of said last rock shafts whereby rocking movements of said first rock shaft operates to rock said second rock shafts in opposite directions, and means for operatively connecting said last rock shafts to said blank-holder for reciprocation thereof.

In testimony whereof I have hereunto signed my name to this specification.

ARTHUR A. BYERLEIN.
